ATTYS

UNITED STATES PATENT OFFICE.

HAROLD FREDERIC SECRETAN, OF PELAW-ON-TYNE, ENGLAND, ASSIGNOR TO A. REYROLLE & COMPANY LIMITED, OF HEBBURN-ON-TYNE, DURHAM, ENGLAND, A BRITISH COMPANY.

ELECTRIC WALL PLUG.

Application filed September 19, 1923 Serial No. 663,664.

To all whom it may concern:

Be it known that I, HAROLD FREDERIC SECRETAN, a subject of the King of England, and residing at Pelaw-on-Tyne, Durham, in England, have invented certain new and useful Improvements in Electric Wall Plugs, of which the following is a specification.

This invention relates to electric wall plugs and has particular reference to plugs of the type in which the pins are surrounded by a casing preferably of metal and earthed. In order that access to the pins and their connections may be readily obtained, according to this invention the casing or cover is divided say into two parts which are held together by a screwed collar or other easily removable fastening, this member preferably also forming a cord grip.

In one convenient construction the casing is cylindrical and is provided at one end with a cap on the inside of which the insulating block holding the pins is mounted. A tubular extension projects sideways from the casing, part of this tube being integral with or attached to the cap and the other part integral with the cylindrical portion. This tubular extension is screwed and when the cap is in place the two parts of the tube are engaged by a screwed collar which holds the two portions of the casing firmly together. Conveniently the screwed collar has an internal flange at its outer end serving directly or indirectly to compress a rubber gland which surrounds the conductors which pass through the tubular extension, thus causing the gland to act as a cord grip. That part of the insulated conductor adjacent to the tubular extension may be surrounded in a well known way with a short length of flexible metallic tubing acting as a guard and the screwed collar may be arranged to press the end of this metallic tubing firmly against the rubber gland.

The cap may be provided with a recess containing a screw and washer or similar connection for an earthing wire which may thus be sunk below the surface of the cap, thereby protecting the hand of the operator from damage.

If desired the cap may be provided with

a pivoted handle so that the wall plug may be readily removed from its socket.

In the accompanying drawings,

Figure 1 is an elevation of one construction of plug according to this invention with a portion broken away, and

Figure 2 is a plan.

Like letters indicate like parts throughout the drawings.

A (Figure 1) is a block of insulating material in which contact pins B are mounted and connected to the ends of the conductors in a flexible cable C. Details of this block, the pins and connections are not shown as they may be of usual construction and do not in themselves form part of the present invention.

The metal cover or casing is in two parts, a cylindrical portion D and a cap D'. The cylindrical portion D is provided with an extension D² in the form of a half tube and the cap D' with a similar extension D³. When the two parts of the casing are assembled the two half tubes, which are screwthreaded, form a screwed tube which is engaged by a screwed collar E. This collar holds the two parts of the casing securely in position but when it is withdrawn allows the cap D' and its extension D³ to be lifted off, giving ready access to the block A and the connections to the pins B.

In the example illustrated the screwed collar E also serves as a cord grip as, when it is screwed on, it compresses a rubber washer or collar F between the end of the tube formed by the extensions D² and D³ and the end of a short flexible sleeve or guard G through which the cable C passes, the end of this guard being engaged by the collar E.

In the top of the cap D' is a recess D⁴ containing a washer and screw H which afford a convenient attachment for an earthing wire when such a connection is used.

In the example illustrated the cap D' is shown as furnished with a pivoted handle J. This does not necessarily form part of the invention but is convenient as affording a ready means whereby the plug connection may be removed from the socket with which it cooperates.

It will be understood that the details of

construction may be varied, for instance the two parts of the casing need not necessarily be secured together by means of the screwed collar E, some other device, such 5 for instance as a sliding collar with a bayonet joint, being used for the purpose.

What I claim as my invention and desire to secure by Letters Patent is:—

1. In an electrical attachment plug, in combination, a sleeve portion, a cap closing one end thereof, an insulating block carried by said cap, contacts mounted in said block and protected by said sleeve portion, a half tubular extension on each said sleeve portion and 15 said cap and detachable means securing said half tubular extensions together to hold said cap and sleeve in proper relation and to house a conductor.

2. In an electrical attachment plug, in combination, a sleeve portion, a cap for one end thereof, an insulating block carried by said cap, contacts mounted in said block and

protected by said sleeve portion, a half tubular extension projecting radially from each said sleeve portion and said cap and detachable means to engage said half tubular extensions to secure the same together for the purpose described. 25

3. In an electrical attachment plug, in combination, a sleeve portion, a cap for one 30 end thereof, an insulating block carried by said cap, contacts mounted in said block and protected by said sleeve portion, a half tubular extension projecting radially from each said sleeve portion and said cap, a conductor connected to said contacts, a protecting sleeve thereon, and detachable means to engage and secure said half tubular extensions together and to secure said sleeve thereto. 35

In testimony whereof I have signed my name to this specification.

HAROLD FREDERIC SECRETAN.
